TIRE

Frank Herzegh, Cleveland, Ohio, assignor to The B. F. Goodrich Company, New York, N. Y., a corporation of New York

Application August 30, 1957, Serial No. 47,556

Term of patent 14 years

(Cl. D90—20)

Fig. 2

Fig. 1

Fig. 1 is a perspective view of a tire showing my new design it being understood that the full line portions are repeated throughout the circumference of the tire shown by means of broken lines; and

Fig. 2 is a fragmentary view thereof drawn to an enlarged scale.

The dominant features of my design reside in the full line portions of the drawing.

I claim:

The ornamental design for a tire, as shown and described.
